186,989

CONDIMENT SPREADER

Harry Leroy Pearson, Jr., Norfolk, Va.

Application December 31, 1958, Serial No. 53,998

Term of patent 14 years

(Cl. D44—22)

Fig. 1 is a view in perspective of a condiment spreader, showing my new design.

Fig. 2 is a top plan view of the same.

Fig. 3 is an end elevation with portions broken away and shown in section.

Fig. 4 is a bottom plan view.

Fig. 5 is a rear elevational view.

I claim:

The ornamental design for a condiment spreader, as shown.
